MASSAGING TABLE

George Byers, Los Angeles, Calif.

Application January 3, 1940, Serial No. 312,193

4 Claims. (Cl. 128—73)

My invention relates to a massaging table and has for its principal objects, to generally improve upon and simplify the construction of the existing forms of massaging and adjusting tables and to provide a relatively simple, practical and highly effective table whereby rhythmic stretching movement may be conveniently applied to the body and particularly the spine, back, legs and hips, and which stretching movements and the alternate relaxation of the body imparts gentle exercise and massaging action in the general treatment of various ailments or irregularities of the spine, muscles, ligaments, tendons, and other portions of the body.

With the foregoing and other objects in view, my invention consists in certain novel features of construction and arrangement of parts that will be hereinafter more fully described and claimed and illustrated in the accompanying drawing in which:

Fig. 1 is a side elevational view with parts in section of my improved massaging table.

Fig. 2 is a plan view of the table with parts broken away and in section.

Fig. 3 is a cross section taken on the line 3—3 of Fig. 2.

Referring by numerals to the accompanying drawing which illustrates a preferred embodiment of my invention, 10 designates a flat table top supported by legs 11 and which table top supports the motor and other operating parts of the massaging table.

Connected by a suitable hinge 12 to the front end of the table top 10 is a flat panel 13, preferably formed of wood or pressed sheet metal, and which is of sufficient length and width to receive and support the body of the user of the apparatus.

Removably positioned on the main body portion of the panel 13 is a pad or cushion 14 for the body of the patient and arranged on the outer end portion of the panel is a pad or cushion 15 for the head of the user.

Suitably secured to the under side of the panel 13 are the upper ends of depending threaded rods 16 upon the lower portions of which are mounted manually operable nuts 17 and the latter being held for rotation in suitable housings 18 that are secured to the floor.

The construction just described enables that portion of the table opposite the end that is hinged to the table 10 to be adjusted so as to occupy different inclined positions that may vary in accordance with the treatment given by the apparatus.

10 Suitably secured to the sides of the table 13 adjacent the end that is supported by the adjustable members 16 are longitudinally disposed angle bars 19 and formed in the horizontal flanges thereof adjacent the end of the table 13 are longitudinally disposed slots 20. Overlying the slotted portions of the angle bars 19 are the ends of a transverse bar 21 and passing therethrough and through the slots 20 in the bars 19 are bolts 22, on the lower ends of which are mounted nuts 23 and which arrangement enables the transverse bar 21 to be adjusted lengthwise upon the slotted ends of the bars 19 and to be clamped to said bars after such adjustment.

15 Formed in transverse bar 21 are short longitudinally disposed slots 24, through which pass bolts 25 and said bolts also pass through brackets 26 that are loosely mounted on top of the cross bar 21 and which brackets carry upstanding head rests or pads 27. The bolts 25 operating in the slots 24 enable the head rests to be adjusted toward and away from each other in order to comfortably support the patient's head and the tightening of the bolts secures the head rests in position after adjustment.

20 Formed in the horizontal flanges of the angle bars 19 adjacent the ends opposite the ends in which the slots 20 are formed are slots 28 through which pass bolts 29 and the latter also passing 30 through plates 30 that are mounted for sliding movement on top of the bars 19 and each bar carrying an upstanding padded bracket 31, which latter provide supports for the elbows of the user of the table.

25 Mounted on the rear portion of table 10 is an electric motor 32 with which is associated a reduction gear box 33 and projecting from the latter is one end of a horizontally disposed shaft 34. Mounted on the projecting end of this shaft 40 is a crank arm 35 provided with a longitudinally disposed slot 36 in which is adjustably mounted a wrist pin 37 and upon which is journaled one end of a pitman 38.

35 Secured on table 10 in front of the motor are 45 pairs of aligned bearings 39 and mounted for reciprocatory movement in said bearings are parallel rods 40. Secured to the intermediate portions of the rods 40 are the lower ends of upright frames 41 and connecting the intermediate portions of said frames is a cross rail 42. Pitman 38 is journaled to the intermediate portion of cross rail 42 and thus as shaft 34 is rotated, reciprocatory movement will be imparted to the frames 41 and to the rods 40.

50 55 Secured to the inner side faces of the upright

frames 41 above and below the cross bar 42 are brackets 43 and passing through each bracket is a horizontally disposed rod 44. Set screws 45 are seated in the brackets 43 and when tightened, these set screws clamp the rods 44 to said brackets.

Carried by the forward ends of each pair of rods 44 are vertically disposed panels 46 provided on their front faces with pads 47, thereby providing cushioned rests for the feet of the user of the table.

Secured to the sides of each panel 46 are short horizontally disposed straps 48 and connected to the free ends of these straps are straps 49 adapted to pass around the legs of the user just above the ankle bones.

In the use of my improved massaging table, the patient lies recumbent on the table 13 which latter may be adjusted to the desired inclination by manipulation of the nuts 17 on the supports 16 with the head resting on the cushioned supports 27, the elbows bearing against the cushioned brackets 31 and with the feet connected to the cushioning panels 46 by the straps 48 and 49.

The motor is now started and through crank arm 35 and pitman 38 reciprocatory movement will be imparted to the frames 41 and rods 40 that operate in the bearings 39.

The rods 44 that carry the foot panels 46 are clamped to the frames 41 by the set screws 45 and thus as the frames 41 reciprocate, the body and legs of the patient will be intermittently stretched and between the stretching movements the body will relax and which movements impart mild exercise and massaging action to the entire body and particularly to the limbs, back and spine.

For best results the speed of the motor should be such as to impart fifty strokes per minute to the reciprocating frames that carry the foot pads and the length of stroke of the reciprocating parts may be anywhere from two to four inches.

For ordinary body massage and exercise, the supports 16 should be adjusted so that the end of the table occupied by the head of the patient is approximately six inches lower than the end that is hinged to table 10 and thus, when pulling strains are exerted upon the body the weight of the latter is sufficient to yieldingly resist the proper amount of stretch imparted to the legs, hips, and spinal column.

The rhythmic reciprocating movement of the table brings about a direct action upon the cartilages between the vertebrae of the spine inasmuch as the entire spine is alternately stretched and then permitted to relax and contract, which action intermittently releases the pressure upon the cartilages and then compresses the same with a very beneficial massaging action.

The alternate stretching and relaxation of the spinal area brings about an increased supply of blood to the perichondrium, the fibrous membrane that surrounds the cartilages, and it is from the vessels of this membrane that the cartilages receive their nutritive fluid. This increased blood circulation and supply renders the cartilages more healthy and resilient and materially assists the same to perform their normal functions.

The intermittent stretching of the body tends to relieve nerve pressure upon the spine, thus bringing about increased nerve energy to the various organs of the body, and the movement of the body backward and forward upon the gluteus muscles produces a gentle massage to the sciatic nerve, tending to relieve congestion and ma-

terially increasing blood circulation through the adjacent muscles and tissues.

During treatment, the position of the patient's body with the head lower than the feet, combined with the reciprocating movements, tends to relieve the downward pressure of the organs within the abdomen so as to enable the same to assume their normal positions and consequently permitting normal functions of said organs.

Such reciprocating movement gently massages the intestines, liver, kidneys, and gall bladder, which tends to relieve congestion and aids materially in elimination from the bowels and kidneys. The blood pressure of the lower extremities is materially lessened and the circulation of blood is materially increased throughout the upper portion of the body, the neck, the head.

The padded foot supporting members 46 are independently adjustable for the accommodation of patients having legs of different lengths, that is, one leg shorter than the other.

It is to be understood that the head rests 27 and elbow rests 31 are not essential to the successful operation of the table and, therefore, said parts may be eliminated in the majority of treatments and used only in special cases.

Thus it will be seen that I have provided a massaging table that is relatively simple in construction, inexpensive of manufacture and very effective in performing the functions for which it is intended.

It will be understood that minor changes in the size, form and construction of the various parts of my improved massaging table, may be made and substituted for those herein shown and described, without departing from the spirit of my invention, the scope of which is set forth in the appended claims.

40 I claim as my invention:

1. In a massaging table, a support, a one piece body supporting table positioned in front of and hinged to said support so as to swing bodily on a horizontal axis, the tops of said table and support occupying substantially the same horizontal plane, means for raising the other end of the table so as to vary the inclination thereof, pairs of aligned bearings on said support, rods arranged for sliding movement in said bearings, an upright frame secured to said rods, a motor mounted on said support, driving connections between said motor and said upright frame, brackets on said upright frame, rods adjustably seated in said brackets, means for clamping said rods to said brackets in differently adjusted positions, foot supports carried by the forward ends of said rods and means carried by said foot supports for engaging the ankles of the occupant of the table.

60 2. In a body stretching and massaging apparatus, a table, rails mounted on the sides of said table at one end thereof, said rails being provided with slots, plates adjustably positioned on said rails above the slots therein, means passing through said plates and through the slots in said rails for clamping said plates to said rails in differently adjusted positions and elbow rests secured in said adjustable plates.

70 3. In a body stretching and massaging apparatus, a table, rails mounted on the sides of said table at one end thereof, said rails being provided in their end portions adjacent the end of the table with longitudinally disposed slots, a bar extending across the table with its ends bearing on the slotted portions of said rails, means pass-

ing through the ends of said bar and the slots in the rails for clamping said bar to said rails in differently adjusted positions and head rests adjustably mounted on said cross bar.

4. In a massaging table, a support, a one piece body supporting table positioned in front of and hinged to said support so as to swing bodily on a horizontal axis, the tops of said table and support occupying substantially the same horizontal plane, means for raising the other end of the table so as to vary the inclination thereof, rails mounted on the sides of said table at one end thereof, said rails being provided with slots, plates adjustably positioned on said rails above the slots therein, means passing through said

15 plates and through the slots in said rails for clamping said plates to said rails in differently adjusted positions and elbow rests secured to said adjustable plates, pairs of aligned bearings on said support, rods arranged for sliding movement in said bearings, an upright frame secured to said rods, a motor mounted on said support, driving connections between said motor and said upright frame, rods adjustably seated in said brackets, means for clamping said rods to said brackets in differently adjusted positions, foot supports carried by the forward ends of said rods and means carried by said foot supports for engaging the ankles of the occupant of the table.

GEORGE BYERS.
